SWEATBAND

Bernhard J. Drueding, Philadelphia, Pa.

Application October 22, 1934, Serial No. 749,408

2 Claims. (Cl. 2—181)

This invention relates to hats, and has for an object to provide the sweatband of a hat of new and improved type.

A further object of the invention is to provide a hat with a sweatband of substantially the usual material and type, but with an added absorbing and cushioning unit applied thereto, said unit extending beyond the edge of the sweatband proper, and offering means for sewing the sweatband to the hat at that location, the sweatband proper remaining unsewed between the pad and the hat crown.

A further object of the invention is to provide a pad occupying a position at the anterior of the hat, for engagement with the forehead of the wearer for comfort, and composed of material for both cushioning and absorbing perspiration, also serving to secure the sweatband within the hat, which band remains free from stitching or other attachment, at the location of the pad, adding to the cushioning effect of the pad.

The invention, therefore, comprises in combination with a hat of the usual crown and brim construction, of a sweatband of the usual and ordinary material having applied thereto at the anterior position of a hat a pad which will be on the interior of said band in proper position for engagement with the forehead of the wearer, said sweatband being stitched to the junction of the crown and brim in the usual manner throughout its entire length, except that part which is covered by the pad and at that location allowed to remain free of stitching, the connection being provided by the stitching of the edge of the pad to the junction of the crown and brim, said edge extending below the edge of the sweatband for that purpose.

The drawing illustrates an embodiment of the invention and the views therein are as follows:

Figure 1 is a view in elevation of a fragment of a sweatband with the pad attached.

Figure 2 is a section from the anterior to the posterior through a hat, and through the sweatband and pad.

Figure 3 is an enlarged detailed fragmentary view, similar to that shown at Figure 2 and defined by the circle 3 at Figure 2, and

Figure 4 is a transverse sectional view taken on line 4—4 of Figure 1.

Like characters of reference indicate corresponding parts throughout the several views.

The present invention is directed to a hat, or more particularly to the sweatband of a hat which is adapted to be associated with a hat of substantially any usual and ordinary type, as for

instance, one with a crown 10 and brim 11, while it is to be understood that the invention is in no way limited to the particular type shown, which is merely for illustration.

A sweatband 12 of the usual material is applied. Ordinarily, this sweatband is of leather, but the present invention is in no way limited to that material and will include sweatbands of any and all materials.

Upon that part of the sweatband which will engage the forehead of the wearer, that is to say, the anterior part of the hat, a pad 13 is provided. At Figure 1 especially, this pad is shown as having a shape as there shown, but it is to be understood that it is merely illustrative, and that the shape may be varied as may be found desirable. This pad may also be of a great variety of material, but is preferably of some material of soft nature having a smooth surface, such for instance, as suede or chamois, among the leathers, or felt or similar materials among the fabrics. Such materials are, however, mentioned merely by way of illustration, without limitation.

This pad is secured to the sweatband in any approved manner. As indicated in the drawing, it is stitched as at 14, but this is merely a convenient, and at the present considered a preferred, way of attaching, but is not a limitation upon the attaching of the pad in any other manner, or by any other means.

Normally, the lower edge of the band, as it is applied to the hat, is curved and is stitched to the hat at the junction of the brim and crown, as indicated at 15. It is obvious, of course, that any other approved type of fastening or securing may be employed.

The pad 13 has along its lower edge a curvature 16 of shorter radius than the curvature of the band itself, so that at its middle it extends a considerable distance below the edge of the band, as shown more particularly and understandably, at 17 at Figure 4. From this position of greatest extension it tapers to its opposite ends where the ends substantially coincide with the edge of the sweatband itself.

When the band is stitched into the hat by the stitches 15, the stitches are through the edge of the sweatband throughout all that area, excepting that covered by the pad 13, and at this point the stitching runs off from the edge of the sweatband, as shown at Figures 1 and 3, and the stitching unites only the pad 13 to the junction of the brim and crown, the edge of the band being raised above such stitching to the

position shown more particularly at 18 in Figure 3.

By reason of the raising of the sweatband at this location, a curvature is given to the band which, operating at the rear of the pad, adds a cushioning effect to the pad, providing a resiliency not resident in such material as the pad is composed of. The hat as constructed presents to the wearer an area contacting with the forehead of far greater comfort, by reason of its yielding, both of the pad proper and the resiliency of the unattached part of the sweatband, than is found where the sweatband is attached throughout its entire lower edge, even with a pad of similar nature applied in the same position. In other words, the attaching of the band at that position by the stitching through the edge of the pad, the edge of the band proper remaining unattached, provides for a yielding, resiliency and cushioning effect not otherwise provided.

Of course, the sweatband described may be modified and changed in various ways without departing from the invention herein set forth and hereinafter claimed.

I claim:—

1. The combination with a hat, of a sweatband encircling the interior of the hat and having an edge attached thereto throughout the larger part of its length, and a pad applied to and within the concavity of the sweatband and extending below the edge, said extended edge being attached to the hat throughout its length with the underlying part of the sweatband unattached. 5

2. The combination with a hat comprising a crown and brim, of a sweatband encircling the interior of the crown, stitches connecting the lower edge of the sweatband to the hat at the junction of the crown and brim, said stitching 10 extending throughout the larger portion of the band but providing an unstitched area at the anterior of the hat, and a pad secured to the interior of the sweatband and having its lower edge extending below the edge of the sweatband, 15 said lower extended edge being stitched to the junction as a continuation of the stitching of the lower edge of the sweatband. 20

BERNHARD J. DRUEDING.
